M. E. RUSCH

TRAFFIC REGULATOR

Filed Nov. 13, 1925

INVENTOR:
Matthew E. Ruch
BY David E. Carlsen
ATTORNEY.

UNITED STATES PATENT OFFICE.

MATHEW E. RUSCH, OF ST. PAUL, MINNESOTA.

TRAFFIC REGULATOR.

Application filed November 13, 1925. Serial No. 68,767.

My invention relates to a signal apparatus for regulating traffic at road and street intersections and like places. The object of the invention is to provide a simple, novel and efficient stop and go signal device embodying a new type of illuminated dials and indicator hands with clockwise movement indicating the duration of either the stop or go signal.

10 In the accompanying drawing:

Fig. 1 is a front view of my improved traffic regulator in operative position, its lower portion shown in section to reveal the driving mechanism.

15 Fig. 2 is an enlarged horizontal section of the signal housing 10 about as on line 2—2 in Fig. 1.

Fig. 3 is a vertical section on line 3—3 in Fig. 2.

20 Figure 4 is mainly a section on line 4—4 in Fig. 2 and a wiring diagram.

Fig. 5 is an enlarged horizontal section of the signal housing 10 about as on line 5—5 in Fig. 1.

25 Referring to the drawing by reference numerals 10 designates the signal housing of my device preferably made of sheet metal with four rectangularly arranged openings each closed by a circular dial made of two half round plates of glass placed edge to edge vertically. Said glass plates carry the words "Stop" and "Go" the first preferably on red translucent glass 11^a and the latter on translucent green glass 11^c.

30 35 12 are four vertical partitions (see Fig. 5) radiating from the center part of the housing 10 and terminating each near the inner face of a dial and in alignment with the meeting edges of the glass therein.

40 45 13 is a vertical hollow column supporting the signal housing at any suitable elevation and 16 is a base or enlargement of the lower end of the column adapted to be suitably fixed on a pavement, 17 is a vertical drive shaft suitably journaled within the column and its upper end carrying a bevel gear 18 constantly meshing with four pinions 19 each on a shaft 20 extending horizontally from gear 18. Each shaft 20 is suitably journaled as in a bearing 21 of a bracket 21 in housing 10.

50 On the inner face of any one of the dials I secure concentric with shaft 20 a ring 22 of electroconductive material except at its diametrically opposite top and bottom parts 22^a and 22^b where the material is non-con-

ductive. 28 is a dial hand secured on the outer end of each shaft 20 its point normally in contact with ring 22 and closing an electric circuit except at points 22^a and 22^b. 60 Each section of ring 22 is electrically charged by a battery 25 suitably connected by circuit wires 23. 24^a, 24^b, 24^c and 24^d are suitable electric bulbs in the circuits 23, each bulb in one of the rooms or compartments 65 formed by any two adjacent walls 12 and dials 11^a—11^b. These compartments are designated A, B, C and D in Fig. 5.

Assuming that traffic is supposed to proceed in the direction of arrows 27 (Fig. 5) 70 the Go signal is illuminated in rooms or compartments A and D by the bulbs 24^a and 24^c simultaneously and the red glass 11^b in each of said compartments is simultaneously illuminated to indicate Stop of traffic at 75 right angles to Go traffic. In Fig. 4 is clearly shown that the hand 28 rotating in the direction of arrow 29 on the Stop side of the ring 22 allows current from battery 25 to pass through the electric lights 24^a and 24^c 80 through ring 22, finger 28, shaft 20 and back to battery through wire 23^a. Thus the Stop signals readable in direction of arrows 26 are illuminated by the bulbs 24^a and 24^c while the hand 28 is traversing the dial, until the 85 circuit is broken at 22^b. The said bulbs are simultaneously illuminating the Go dials in direction of arrows 27. When the circuit is broken at 22^b the finger 28 continues to the right half of the ring 22 (Fig. 4) and 90 closes circuit in like manner to bulbs 24^b and 24^d and traffic is directed to move or stop accordingly at right angles to the course just described until the circuit is again opened at 22^c, etc. It is obvious that steady 95 rotation of shaft 17 will cause traffic to be directed in both directions for equal periods of time.

The driving means for shaft 17 may be widely varied in construction to rotate the 100 dial hands at different speeds. I have shown a large and a small bevel gear 30 and 31 respectively at the lower end of shaft 17 and engaged respectively by pinions 32 and 33 of which pinion 32 is driven by a motor 105 34 and pinion 33 by a motor 35. Both motors may be of the type having a switch lever 36 which may be set for various speeds. It will be readily understood that at intersections where traffic is heavier in one direction than the other the Go signal will need 110 to be illuminated longer than the Stop sig-

nal in the direction of heaviest travel. This means that the dial hands must travel slower on one side than on the other. This may be accomplished by any suitable speed changing gears (not shown) or the speed of shaft 17 may be changed by switching current from one motor as 34 to the other as 35 or vice-versa by the circuit closing and opening means of one dial ring 22.

10. The common practice in traffic signals is to illuminate the word "Stop" in red letters and the word "Go" in green letters. This may be adhered to in my traffic signal also though it is obvious other colors may be used. Each dial of my device comprises two pieces of semicircular glass, as previously stated, one of which is translucent green glass with a transparent green area in the form of the word "Go". The other glass 20 is translucent red with an area of transparent red in the form of the word "Stop". Thus when the signal is in operation and the "Stop" is illuminated the said word is displayed in very bright color and the shadow of the dial hand moving just inside the dial can be seen moving toward the "Go" side of the dial, and vice-versa. Persons whose movement is thus directed can readily see at what stage the "Stop" or "Go" 25 is in and prepare to stop or go accordingly. It is obvious that all the moving parts of my device are entirely inclosed and not exposed to the elements.

What I claim is:

30. 1. In a traffic signal a housing, a dial in a wall of said housing formed of a plurality of complementary translucent sections in-

cluding Go signal means for one and Stop signal means for another of said sections, a pointer, means mounting said pointer for movement over said dial, means for continuously moving said pointer over said dial, illuminating means associated with each section of said dial for illuminating said section, a circuit for each illuminating means, and means including said pointer foreclosing the circuit for the illuminating means for that section over which the pointer is moving.

2. The structure specified in claim 1, in which said circuit closing means comprises additional to each said hand, a split electro-conductive ring fixed to the inner side of the dial and comprising two parts one in each signal circuit said parts being electrically separated, said hand continuously in contact and movable on said ring for closing circuit to the said illuminating means.

3. The structure specified in claim 1, in which said circuit closing means comprises additional to each said hand, a split electro-conductive ring fixed to the inner side of the dial and comprising two parts one in each signal circuit, said parts being electrically separated, said hand continuously in contact and movable on said ring for closing circuit to the said illuminating means, the latter means comprising an electric light bulb for illuminating one side of a dial as the said hand traverses the illuminated side of the dial.

In testimony whereof I affix my signature.

MATHEW E. RUSCH.
